CLAIM

The ornamental design for a gear construction toy, as shown and described.

DESCRIPTION

FIG. 1 is a front perspective view of a gear construction toy having ten gear teeth showing my new design, the rear perspective view being identical;

FIG. 2 is a top plan view of a first alternative embodiment of the gear construction toy of FIG. 1 having nine gear teeth;

FIG. 3 is a front elevational view thereof, the rear elevational view being identical;

FIG. 4 is a right side elevational view thereof, the left side elevational view being identical;

FIG. 5 is a bottom plan view thereof; and,

FIG. 6 is a perspective view of a second modified embodiment of the design shown in FIGS. 1-5.

FIG. 2.

FIG. 3.

FIG. 4.

FIG. 5.

FIG. 1.

FIG. 6.
